UNITED STATES PATENT OFFICE

2,422,552

PREFLIGHT PILOT TRAINING AIRCRAFT APPARATUS

Volmer S. Jensen, Glendale, Calif., assignor to California Aero Glider Co., Inc., a corporation of California

Application August 16, 1943, Serial No. 498,757

6 Claims. (CL. 35—12)

1

This invention relates to and has for an object, the provision of an air pilot training apparatus constructed and arranged as nearly as possible to conform to an airplane but adapted to be stationarily mounted in a class room and provided with elements and controls therefor which, when a trainee is in the pilot's position, will afford the trainee an idea of conditions encountered in the operation of an airplane when in flight.

The invention comprehends the provision of a small scale model of a real airplane, capable of holding and under control of a pilot and provided with a fuselage, wings, ailerons, a rudder, and a controlling mechanism operable by the pilot in a manner similar to conventional airplane controls, together with a standard upon which the model is freely rotatable and universally movable as to inclination laterally and longitudinally.

Another object is to provide on such an apparatus a motor driven propeller, the axis of which is adjustable at the will of the pilot and relative to the axis of the motor spindle for effecting rotation of the trainer about a vertical axis while the body is freely tiltable in any direction and at a point in a revolution thereof by operation of the aileron and elevator controls.

A still further object is to provide longitudinal and transverse resilient connections between the fuselage and the supporting standard for tensioning and stabilizing the fuselage.

Other objects may appear as the description of my invention progresses.

I have shown a form of apparatus embodying my invention in the accompanying drawings, in which:

Fig. 1 is a top plan view;

Fig. 2 is a side elevation;

Fig. 3 is a fragmentary section of the means for supporting the fuselage on the standard, as seen on line 3—3 of Fig. 1.

Fig. 3A is a fragmentary sectional elevation of the lower end of the supporting standard.

Fig. 4 is a front elevation;

Fig. 5 is a diagrammatic sectional elevation on line 5—5 of Fig. 1; and

Fig. 6 is a fragmentary plan on line 6—6 of Fig. 5.

In a conventional manner, though on a small scale, an apparatus embodying my improvements includes a fuselage A with a cockpit 1 adapted to seat a pilot trainee, a rudder B at the rear having relatively fixed and adjustable members 2 and 3, an elevator C having fixed stabilizing portions and relatively adjustable portions 5, and

wings D having adjustable ailerons 6. All of said elements are mounted as a unit on a suitable standard E having a base 7 formed with a plurality of wide spreading legs 8, 8, etc. and a central vertical standard 9 rigidly fixed at its bottom to the base and extended upwardly into the interior of the fuselage at a point substantially at the center of gravity of the fuselage.

Standard 9 is rotatable on a stationary post 9a, and may be provided at its top with a suitable ball bearing 10 or other type of anti-friction bearing adapted to receive a socket 11 carried by a skeleton frame 12 which has a plurality of arms 13 inclinably disposed and attached at their lower extremities to the floor of the fuselage, said floor having an aperture 14 which is of sufficient diameter to permit the tilting of the fuselage to a desired extent during training operations. Standard 9 has an extension 9' which may be welded to the standard and suitably supports the ball 10. Socket 11 may have a nut 11' screwed into its upper end and a bearing member 10' confined in the socket between said nut and ball 10 as shown in Fig. 3. Standard 9 is preferably of tubular cross section and carries ball bearings 9b and 9c (Figs. 3 and 3A) at its top and bottom, respectively, for rotatably supporting the same on post 9a.

Wings D are braced by rods 15, 15 arranged in pairs on opposite sides of the fuselage and are disposed diagonally with their upper extremities secured to the fuselage and their lower extremities secured to the tops of the wings at points substantially outwardly of the fuselage so as to afford adequate rigidity.

A motor F, (Figs. 4 and 5), is adjustably mounted in the nose of the fuselage and serves to rotate a propeller G under the control of a pilot seated in the cockpit 1, said motor being adjustable on a vertical axis in order that the propeller may be swung to the right or left at the will of the pilot, and connected with rudder B so as to effect rotation of the fuselage on the axis of the standard 9 in a desired direction. Motor F is mounted on a suitably pivoted support 16 to which a pulley 16a is fixed and on which a sleeve 16b is rotatably held.

I provide the usual stick H which is pivotally mounted at 17 on the floor of the fuselage and is arranged for connection at points below the fulcrum 17 with the ailerons 6, 6, as by means of cables 18, 18, respectively. Said cables are attached to fixtures 19, 19, on the ailerons and operate over pulleys 20, 20, on the lower sides of wings D, D, and are suitably connected with por-

tions 21, 21 of the stick H, (Fig. 4), so that the movement of the stick laterally will correspondingly incline the associated ailerons in a desired direction and to a desired extent.

Portions 5, 5, of the elevator C are transversely connected for simultaneous operation and are suitably hinged to the stabilizing (fixed) portions 4, 4, by suitable means. Said portions 5, 5, are connected with the stick H, as shown in Fig. 5, by means of a cable 22 fixed at its rear end to a member 23, and at its forward end to a point 24 on the stick. The portions 5 are tensioned as by means of a spring 25 attached at its opposite ends to a member 26 on one of the portions 5, and at its forward end to a lug 27 on fuselage A. Thus, spring 25 tends to tip the portions 5 upwardly while the forward movement of stick H serves to tip said portions downwardly.

The elevator and the stick are held in normal or neutral position, however, by the opposing tension of a control spring 28 which is tensioned between a point of attachment 29 to standard 9 and a point of connection 30 with stick H, and utilizing a cable 31 operable over pulleys 32 and 33 and anchored, respectively, to the bottom of the fuselage and motor support 16 (Fig. 5).

Thus, stick H, through its connections with ailerons 6, 6, controls the lateral tilting of the craft, and through its connections with the elevator controls the longitudinal tilting thereof.

It may be noted, however, that the arrangement of the controls is such that the mounted craft is normally stable and so to speak, on an even keel. In other words, the craft when static is balanced as shown in Figs. 2 and 5. Hence, in opposition to spring 28 a spring 34 is employed for connection between the standard 9 and stick H and is secured at a point 35 to said standard and at its other extremity to a cable 26 which operates over pulleys 37 and 38, and is attached at or near point 24 to the stick. Pulleys 37 and 38 are attached, respectively, to fuselage A and a convenient portion of standard 9 or to the socket 11 thereon.

Now, it will be observed from the foregoing description that the craft, under control of a pilot, may be tilted laterally and longitudinally at will by manipulation of stick H to simulate forward, climbing or diving movements, and there remains only steering and turning operations to be accomplished. In this respect, attention is directed to the swivelled propeller and the rudder which, in my training apparatus, are arranged to rotate the craft on the axis of the standard 9 and are necessarily connected to such end, and which I will now describe.

Rudder B, as shown in Fig. 1, is tensioned by means of a spring 39, which has one end attached at a point 40 to the fuselage and its opposite end attached to a member 41 on portion 3 of the rudder. Said rudder has an extended member 42 opposite member 41, to which a cable 43 is connected and leads to the right hand end (as viewed by a pilot) of a foot operated cross rod 44 which is fixed to sleeve 16, on the motor support 16.

As shown in Fig. 6, a cable 45 connects an end of cross rod 44 with pulley 16, and has one end fixed to pulley 16, and its other end to rod 44, said cable being operable over an intermediate pulley 46 which is suitably supported on the fuselage. The left hand end of rod 44 is similarly connected with pulley 16 by a cable 47 which operates over an anchored pulley 48. Thus, when pressure is applied to the extended por-

tions of the rod 44, the pulley 16, motor F and propeller G are correspondingly swung on their axes, and with them the rudder B, but it will be noted that motor F and rod 44 swing in opposite directions in order to accommodate the position of the rudder to the adjusted propeller axis. It is desirable, of course, to so arrange the controls that a right hand turn may be effected by a corresponding right hand operation of rod 44, and reversely to negotiate a left hand turn.

However, it is essential that a trainee when operating my apparatus, should learn the operations necessary to actual flying operations, and to such end the controls and the direction of their movement may vary to correspond to modern practise in flying.

My simplified and improved pre-flight training apparatus as herein described and illustrated, lends itself readily and with good results to its employment in connection with a suitable chart, diagram or map, on which may be shown proposed flights, actions, targets, movements and other information which will afford a trainee an idea of what and which particular movements and directions of an airplane to accomplish different and desired results.

As shown in Fig. 4, lateral stability of the craft is controlled by springs 50, 50, attached at points 51, 51, to the bottom of standard 9 and at their opposite ends to cables 52, 52, which operate over pulleys 53, 53, carried by wings D, while the cables 52, 52, are attached to the lower end of stick H. Hence the stick is held in normally upright position when the craft is on an even keel by the tension of springs 28, 34, and 50, 50, and any tilting of the body on its single support 10, either laterally, longitudinally or diagonally, will tension one or more of the control springs.

The standard 9, or the part thereof to which the control springs are attached, may be rotatable on the base so as not to impair the free rotation of the unit to the extent of one or more complete revolutions in either direction.

It will, therefore, be apparent that the mere shifting of the weight of a person seated in the cockpit, may overbalance the body and requires an accurate sense of poise, direction and the functions of the several controls to operate the apparatus.

When the apparatus is assembled and the fuselage mounted on the standard 9 as shown, a trainee is installed in the cockpit and may familiarize himself with the controls and their effect on the stability of the machine. When the motor is started the tendency to non-rotation or the extent of rotation of the fuselage and its associated elements will depend upon the positions of the ailerons, rudder and elevator, as well as the axial angularity or axial alignment of the motor spindle with the longitudinal axis of the fuselage.

It will be apparent that by but slightly changing the axial angularity of the propeller shaft 65 there will be a tendency to rotate the craft in the direction of the angle of adjustment, and the position of the rudder will either tend to accelerate or retard such rotative movement of the craft. Likewise when the craft is rotating the 70 adjustment of the elevators tends to tilt the craft forwardly or backwardly and the tilting of the ailerons similarly tends to tilt the craft laterally in one or another direction against the tension of their respective control springs 28-34, and 75 50, 50.

At all times, however, due to the single support of the craft on its standard, stabilization and control is more or less difficult, depending upon the skill of the trainee. Continued operation of the apparatus develops in a trainee a sense of balance, direction and other values which are essential to actual flight in a motored airplane or glider.

The apparatus is designed and constructed to simulate, as nearly as possible, all of the known movements of an airplane, including straight line flying, rolling, banking, diving, spinning and other movements, and by reason of the fact that the body is freely mounted on but a single universal support (the ball 10) a maximum degree of concentration, sense of stability and coordination of faculties is necessary for its operation. It is not material to this invention but worthy of mention, that some or many of conventionally employed instruments may be employed on my apparatus, such as compass, inclinometer, speed indicators, etc.

Standard 9 may have a collector 55 with a body of insulating material and a pair of rings 56 and 57 thereon adapted to receive brushes 58 and 59 (Fig. 3A) carried by an insulating block 60 attached at a suitable point to a portion of base 7, said brushes being connected with a source of electricity. Electric current is conducted to motor F and other instruments and elements by suitable wiring leading from the collector rings 56 and 57.

It will be noted that in Figs. 2, 4, and 5, I have omitted the collector 55 in the illustration of Standard 9 (as shown in Fig. 3A), as well as the brush mounting 60, for the purpose of more clearly illustrating the assembled apparatus, but it will be understood in the consideration of this invention that the structure of Fig. 3A applies to Figs. 2, 4, and 5 as well.

What I claim is:

1. A pre-flight airplane pilot training apparatus comprising: a stationary standard, a pilot supporting body simulating an airplane fuselage mounted thereon for yawing, pitching and rolling motion and including a fixture attached to and wholly within the body and universally movable on said standard, and including laterally extended wings, an aileron on each wing, a rudder, an elevator, a single manually operable member connected with and for controlling the adjustment of said ailerons and said elevator, a motor mounted on said body, a propeller drivably connected with said motor for rotation on a horizontal axis, said propeller being also bodily rotatable on a vertical axis, and a foot operated control commonly connected to said propeller and to said rudder for simultaneous operation and for regulating the yawing motion of the body.

2. A pre-flight airplane pilot training apparatus as characterized in claim 1, including: resilient connections between said manually operable member, said elevator, and said standard for controlling the pitching of the body on the standard.

3. A pre-flight airplane pilot training appara-

tus as characterized in claim 1, including: resilient connections between said manually operable member, said ailerons and said standard for controlling the rolling of the body on the standard.

5 4. A pre-flight airplane pilot training apparatus as characterized in claim 1, including: connections between the said manually operable member, said elevator, said ailerons and said standard for controlling the rolling and pitching of the body on the standard.

10 5. A pre-flight airplane pilot training apparatus comprising: a stationary standard, a fuselage supported thereon at a single point for rolling, pitching and yawing motion of the fuselage, said standard extending into said fuselage, means within and attached to the fuselage for supporting the fuselage on the standard, a motor mounted in the nose of the fuselage, a propeller drivably connected with the motor, a rudder on the tail of the fuselage, and pilot operated members operably connecting and for correspondingly adjusting the angles of the propeller and rudder simultaneously for changing the yaw of the fuselage on the standard.

15 6. A pre-flight pilot training apparatus comprising: a stationary standard, a body simulating the fuselage of an airplane supported thereon at a single point for universal movement, a motor mounted in the nose of the fuselage, a propeller drivably connected with the motor and having a horizontal axis, a rudder on the tail of the fuselage, and foot operated members operably connecting and for correspondingly adjusting the angles of the propeller and the rudder simultaneously for changing the yaw of the fuselage on the standard, a manually operable member, an elevator connected therewith, a pair of wings each having an aileron also connected with said manually operable member, and spring 20 means connecting said fuselage with said standard at longitudinally spaced points and also at transversely spaced points and tending to restore the fuselage to normal position after the pitching and rolling of the fuselage on the standard.
